UNITED STATES PATENT OFFICE.

THEODORE HAVILAND, OF AMBAZAC, FRANCE.

DESIGN FOR A DISH.

SPECIFICATION forming part of Design No. 22,118, dated January 10, 1893.

Application filed November 22, 1892. Serial No. 452,863. Term of patent 14 years.

To all whom it may concern:

Be it known that I, THEODORE HAVILAND, a citizen of the United States, residing at Ambazac, in the Department of Haute-Vienne and Republic of France, have invented and produced a new and original Design for Dishes; and I do hereby declare the following to be a full, clear, and exact description of the same, reference being had to the accompanying drawing, forming a part thereof.

The design is shown in the figure of the drawing as embodied in a dish having the shape and surface ornamentation of my invention.

15 The leading or characteristic feature of my design is the configuration of the dish provided with a series of ribs A. passing from the

edge in a general direction toward the bottom or away from the margin of the dish. These ribs project at the bottom forming the feet D. 20 of the dish. Between each pair of the ribs are formed medallions E. shield shaped, rising slightly from the surface. At the bottom and top of each shield are ornamental scrolls B. as shown.

25 What I claim is:

The design for a dish substantially as shown and described.

In testimony whereof I affix my signature in presence of two witnesses.

THEODORE HAVILAND.

Witnesses:

A. GALLOU,
L. GIEZILLIE.
